His Attorney.

UNITED STATES PATENT OFFICE.

JOSEPH E. SCHUMACHER, OF LOS ANGELES, CALIFORNIA.

APPARATUS FOR MANUFACTURING PLASTER-BOARD.

1,286,802.

Specification of Letters Patent.

Patented Dec. 3, 1918.

Application filed October 9, 1917. Serial No. 195,661.

To all whom it may concern:

Be it known that I, JOSEPH E. SCHUMACHER, a citizen of the United States, residing at Los Angeles, in the county of Los Angeles and State of California, have invented new and useful Improvements in Apparatus for Manufacturing Plaster-Board, of which the following is a specification.

This invention relates to improvements in apparatus for manufacturing plaster board of the type defined in my pending application for patent for plaster board filed March 16, 1917, Serial No. 155,233; and resides in the provision of inexpensive, simply constructed, easily operable, reliable and effective means for producing surface irregularities, such as openings, in plaster board, so that plaster board thus provided with surface irregularities may be effectively employed to reliably support a wall element such as plaster coatings or the like; such apparatus being disclosed in my pending application for patent, Serial No. 155,233 filed March 16, 1917.

Another and more specific object is to provide apparatus of the character defined which comprises a punch device of such construction that will provide for the punching of peculiarly formed openings through plaster board, said openings having confining walls which are so mutilated, broken or irregularly formed that an effective keying action is provided when plastic coating is applied to the board and enters said openings; the advantage thus derived being the reliable and thorough supporting of the plastic coating by the board.

The invention further consists in the novel and useful association, construction, organization and inter-relation of parts of the apparatus, all as hereinafter described, shown in the drawing and finally pointed out in claims.

In the drawing:

Figure 1 represents an enlarged view of apparatus constructed in accordance with the invention showing the punch in side elevation in the position it would assume after completing a punching operation, and the dies in co-operation with the punch and also the plaster board broken away and in section;

Fig. 2 is a view similar to Fig. 1 showing the punch in the position it would assume prior to the completion of the punching ac-

Fig. 3 is a bottom plan view of the punch;

Fig. 4 is a fragmentary, sectional view through a plaster board showing the peculiar construction of the openings formed by the punch;

Fig. 5 is a top plan view of a plaster board formed with the apparatus embodying this invention;

Fig. 6 is a fragmentary side elevation of a modified form of punch; and

Fig. 7 is a fragmentary plan view of plaster board provided by the modified form of punch shown in Fig. 6.

Referring particularly to the drawing, A designates as an entirety a punch, the shank 2 of which is reduced as at 3 adjacent to its working extremity, such reduced portion 3 constituting the punch proper and being as shown of the rectilinear outline in cross section. In this connection it is to be understood that the cross sectional shape of the punch may be varied as desired, it being preferable, however, to provide for a shape such as illustrated. The lower end of the punch is tapered to a point and formed with facets or end faces 4 which define cutting edges 5 therebetween. The tapered working end is reduced so as to provide a series of shoulders 6 corresponding in number to the faces 4 and which define cutting edges 7. The hereinabove described construction of the working end of the punch is preferable, but it is to be understood that any other suitable formation of said working end may be used as long as the end of the punch is constructed so as to penetrate the plaster board.

There are provided dies B and C for co-operation with the punch A, the die B, having a bore 8 to receive the punch in approximately a working fit, whereas the die C is provided with a bore 9 of a greater diameter than that of the punch so that said punch does not come into contact with the walls of said latter bore. The dies B and C are supported by suitable means, not shown, in facial contact with the plaster board D to be operated upon, the die B being uppermost, whereas the die C is lowermost. The plaster board D comprises a plastic body *a* disposed between facial sheets *b* and *c* of paper or some other fibrous material, such for example as card board.

In the operation of the apparatus, assuming that the dies B and C are positioned relative to the board D as shown in Fig. 1 of

the drawing, the punch 7 is operated so as to penetrate the board D and makes a clean hole in its first penetration of the plaster board D, but as the punching operation proceeds toward the die C, which fails to support the plaster board closely up to the field of the punching operation, the penetrating pressure of the punch tends to advance or push the material of the plaster board into the bore of the die C, or, in other words, to buckle the plaster board to the breaking point or to disrupt the same. It will thus be seen that a clean-cut is made through the facial sheet b of the plaster board, whereas the irregularity of puncture increases in the plaster board body beyond the sheet b and toward the sheet c due to the buckling action of the plaster board; and there is provided a ragged and irregular inner wall for the opening produced by the punch through the board. To insure against the cutting of the paper about the rims of the bore of the die c the upper edge of such bore may be rounded as at c' or otherwise made dull. The facial sheet c is irregularly ruptured and formed into ragged and spaced tongues or ribbons that are directed into the bore 9 as the punch punctures said sheet c, this being illustrated particularly in Figs. 1 and 2 of the drawing. The cutting edges 5 provided at the working end of the punch facilitate the punching operation, making the operation as a whole more accurate and effective. The cutting edges 7 provided by the shoulders 6 cause a clean-cut to be made through the facial sheet b of the board D and likewise produce a scraping action upon the portions of the sheet c which are forced into the bore 9 of the die C. These shoulders 6 together with the cutting edges 7 scrape and remove particles of plastic material from the tongues or ribbons of the sheet c which extend into the bore 9. When the punch is withdrawn the tongues or ribbons, which, for the sake of clearness are designated d, spring or move toward the plane of the sheet b, that is, tend to restore themselves to their normal plane. This is due to the slight inherent spring quality of the material comprising the sheet c, or better, the tongues d.

It will thus be seen that in this manner with the hereinbefore described apparatus, a plurality of openings through plaster board may be provided so that plaster board will be prepared to receive a plastic or cementitious wall coating and to effectively support such coating.

Referring particularly to Fig. 6 it will be seen that there is provided a modified form of punch which is generally designated E. This punch is provided with a reduced tapered working end 10, the reduction of which defines an annular scraping edge 11 corresponding to the scraping edges 7 of the preferred form of punch. The body of

this type of punch is cylindrical instead of rectilinear in cross section, whereas the reduced portion 10 is conical instead of pyramidal in outline. This type of punch operates in the same manner as the preferred form, but provides openings of the general outline indicated in the fragment of board shown in Fig. 7.

It is manifest that many variations in detail of construction of the device as herein described and illustrated, may be made dependent upon conditions concurrent with the adoption of the same, in departure from the foregoing description and statement, but without departing from the spirit and scope of the invention as disclosed.

What I claim is:

1. Apparatus of the character disclosed, comprising die members between which plaster board is adapted to be placed, there being registering openings formed through said die members, and a punch member adapted to extend through said openings, said punch member having a working fit through the opening in the uppermost die member and said lowermost die member having its opening of greater diameter than the punch so as to avoid contact therewith.

2. Apparatus of the character disclosed, comprising a die member adapted to support plaster board, a punch for penetrating the plaster board and having its working end reduced and tapered to a point, the reduction of said working end providing scraping edges, and another die member adapted to be mounted upon the plaster board over the first named die member and having an opening therethrough in which the punch has a working fit, said first named die member having an opening therein of greater diameter than the punch.

3. An apparatus for puncturing plaster board having sheet coverings, and rupturing one of the coverings without severing the ruptured portion of the covering, said apparatus including a die member for the support of the plaster board, and a punch, the opening of the die member having a sufficiently greater diameter than the punch to provide a clearance space for the ruptured portions of the sheet covering when the punch is forced into the die to remove the plaster material from the opening.

4. An apparatus for puncturing plaster board having sheet coverings and rupturing one of the coverings without severing the ruptured portion of the covering, said apparatus including a die member for the support of the plaster board, and a punch having a pointed end and peripheral shoulders at the base of the pointed end, the opening of the die member having a sufficiently greater diameter than the punch to provide a clearance space for the ruptured portion of the sheet covering when the punch is

forced into the die to remove the plaster material from the opening.

5. An apparatus for puncturing plaster board having sheet coverings and rupturing one of the coverings without severing the ruptured portion of the covering, said apparatus including a die member for the support of the plaster board, and a punch which has a pointed end and is provided with cutting edges at the sides of the pointed end, the opening of the die member having a sufficiently greater diameter than the punch to provide a clearance space for the ruptured portions of the sheet covering when the punch is forced into the die member to remove the plaster material from the opening.
6. An apparatus for puncturing plaster board having sheet coverings and rupturing one of the coverings without severing the ruptured portion of the covering, said apparatus including a die member for the support of the plaster board, and a punch which has a pointed end and is provided with cutting edges at the sides of the pointed end, the opening of the die member having a sufficiently greater diameter than the punch to provide a clearance space for the ruptured portions of the sheet covering when the punch is forced into the die member to remove the plaster material from the opening.

paratus including a die member for the support of the plaster board, and a punch constructed with a pointed end and peripheral scraping shoulders surrounding the base of the pointed end, the sides of the pointed end being provided with cutting edges, and the opening of the die member having a sufficiently greater diameter than the punch to provide a clearance space for the ruptured portions of the sheet covering when the punch is forced into the die to remove the plaster material from the opening.

In testimony whereof, I have signed my name to this specification in the presence of two subscribing witnesses.

JOSEPH E. SCHUMACHER.
